[57] **CLAIM**

The ornamental design for a cabinet with sliding display panels, as shown.

DESCRIPTION

FIG. 1 is a top plan view of a cabinet with sliding display panels showing my new design;

FIG. 2 is a front elevational view thereof;

FIG. 3 is a bottom plan view thereof; and,

FIG. 4 is a right end elevational view, the left end being identical thereto.

The rear of the cabinet is flat and unornamented.

FIG. 2

FIG. 1

FIG. 3

FIG. 4
